[57] CLAIM

The ornamental design for an automobile front bumper, as shown.

DESCRIPTION

FIG. 1 is a front perspective view of an automobile front bumper showing the new design as viewed from the top;

FIG. 2 is a front perspective view thereof as viewed from the bottom;

FIG. 3 is a front elevation view thereof;

FIG. 4 is a rear elevation view thereof;

FIG. 5 is a top plan view thereof;

FIG. 6 is a bottom plan view thereof; and

FIG. 7 is a right side elevation view, it being understood that the left side is a mirror image thereof.

FIG. 1

FIG. 3

FIG. 5

FIG. 4

FIG. 6

FIG. 7
